DRAGLINE DEVICE FOR TOYS

John Birrell, Marshfield, Wis.

Application January 19, 1934, Serial No. 707,331

9 Claims. (Cl. 46—48)

This invention appertains to a novel dragline device and more particularly to a novel means for attaching a pull cord or line to toy vehicles, either of the land or water variety.

5 One of the primary objects of my invention is to provide a novel dragline for toy vehicles whereby the toy can be pulled along by the side of a child and made to assume a parallel path forward or backward to the path taken by the child, or a 10 circular path if the child stands still.

Another salient object of my invention is to provide a linkage structure secured to the side of the vehicle for receiving a pull cord, the linkage assuming the form of a trapezium or trapezoid 15 in conjunction with the vehicle when a pull is exerted thereon, whereby the combined forces exerted by the cord on the vehicle will cause the vehicle to assume a straight path forward, irrespective of the fact that the pull on the cord is 20 from the side of the vehicle instead of from the front or rear.

A further object of my invention is to provide novel means for attaching the linkage to the vehicle and the pull cord to the linkage, whereby 25 the vehicle can either be pulled forwardly or rearwardly in a straight path at the option of the child.

A further object of my invention is the provision of novel means for constructing the keel 30 of a toy boat for use with my novel linkage and pull cord, the leading and trailing edges of the keel being provided with a double bevel to insure a direct course of the boat and keep the same perpendicular against waves and currents, the keel 35 acting to aid the linkage and cord in keeping the boat in direct pressure against the water.

A still further object of my invention is to provide a novel dragline for toy vehicles of the above character, which will be durable and efficient in 40 use, one that will be simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawing, in which:

50 Figure 1 is a side elevation of a toy boat showing my improved dragline device connected therewith.

55 Figure 2 is a fragmentary front elevation of the toy boat showing my improved dragline device connected therewith, the linkage and dragline being shown in its extended position.

Figure 3 is a horizontal section taken on the line 3—3 of Figure 2 looking in the direction of the arrows, showing the linkage in full lines in a raised position, but prior to the pulling of the vehicle, and showing the linkage in dotted lines during the pulling of the vehicle, the view illustrating the novel keel construction.

Figure 4 is a horizontal section through the keel of the boat illustrating the novel construction thereof, the view being taken on the line 4—4 of 10 Figure 2, looking in the direction of the arrows.

Figure 5 is a side elevation of a wheeled toy showing my improved dragline connected therewith.

Figure 6 is a diagrammatic view illustrating a 15 preferred arrangement of the wheels on the toy or other vehicle.

Referring to the drawing in detail, wherein similar reference characters designate the corresponding parts throughout the several views, the 20 letter A generally indicates a toy boat and B my novel dragline therefor.

The boat A embodies a hull 10 which can be of any desired size and character supporting an upper structure 11, which can also be of any 25 desired type. The hull 10 includes the depending centrally disposed keel 12 which is constructed in a novel manner.

The keel 12 gradually tapers toward its lower end and the leading and trailing edges thereof are double bevelled. Thus, by referring to Figures 2 and 3, it can be seen that a bevel 13 is formed on one side of the keel from its top and this bevel terminates short of the lower end of the keel. The opposite side of the keel adjacent to its 25 lower end is provided with an oppositely directed bevel 14. These two bevels 13 and 14 tend to hold the boat perpendicular in the water against wave, 30 wind and current action, and aid the dragline B in pulling the boat forward in a straight path by 35 the side of a child. The keel 12 adjacent to its lower end may have weights 15 embedded therein, so as to also aid in preventing the tipping of the boat.

40 My improved dragline device B includes a novel linkage arrangement. This novel linkage arrangement consists of a bail 16 of a substantially U-shape. Thus, the bail 16 includes a straight parallel rod or wire 17 and in-turned angularly extending legs or arms 18, which terminate in eyes 50 or hooks 19. The keel 12 of the boat is provided with screw eyes 20 at spaced points and the eyes 19 and 20 are directly connected or connected by means of links 21, which are preferably in the 55 nature of swivels.

Connected with the rod or wire 17 for sliding movement is the pull cord 22 and I preferably connect the pull cord 22 with the rod or wire 17 by means of a link or swivel 23.

5 The dragline B is preferably connected to the keel with the eyes 20 disposed at the horizontal axis of the boat and on opposite sides of the vertical axis of the boat. The rod or wire 17 is preferably of a less length than the distance between the eyes 20, so that the device normally assumes substantially the form of a trapezoid or trapezium when links or swivels are used.

10 In the use of my improved device, the boat A is placed in the water and a pull is exerted on the cord 22. Due to the links 21, the rod or wire 17 will be pulled forwardly at an angle and made to assume the form of a trapezoid or trapezium (when the links or swivels are used) in conjunction with the keel. The arrangement of the links 15 or swivels and the rod 17 being shorter than the distance between the connections or eyes 20 throws the boat over the center of its horizontal plane, which drives it outwardly against the pull of the cord, whereby the boat will assume a straight, 20 forward path. Obviously, the boat can be pulled backwards by merely exerting a rearward pull on the cord.

25 Naturally, I do not wish to confine the use of my improved toy dragline device to boats alone and the same can be employed in conjunction with wheeled toys. In Figure 5 I have illustrated my dragline device connected with a wheeled toy C, which can be of any desired character, shape or size.

30 35 In this form of my invention, the dragline device is generally indicated by the reference character D and the same includes the U-shaped bail 25, including the rod 26 and the right-angularly extending arms or legs 21, which terminate in the eyes or hooks 28. Secured to the body of the wheeled toy are eyes 29 which are connected directly to the hooks 28 or by means of links 30 to the hooks 28. In this form of my invention, the dragline is also connected to the vehicle at two 40 45 points equidistantly spaced on opposite sides of the vertical axis, the same two points being below the center of gravity and parallel with the horizontal axis.

50 In lieu of using the swivels 21, I can employ the straight links 30, as shown in Figure 5.

55 The pull cord 31 is connected to the rod 26 by means of the swivel 32.

By pulling on the cord, the wheeled toy can be pulled in a straight, forward path, in the same manner as the boat.

60 In order to bring about the best operation of the wheeled vehicle or toy, the front wheels 33 thereof are inclined outwardly toward one side of the vehicle and the rear wheels 34 are inclined inwardly toward the other side of the vehicle.

65 While I have stated throughout the specification that my improved dragline device is particularly intended for toys, I do not wish to restrict myself to the use thereof in connection with toys alone, as the same can be used for a variety of purposes, such as in connection with surf-boards, decoy ducks or different varieties of fishing tackle or any other device with which a dragline may be used.

Changes in details may be made without departing from the spirit or the scope of this invention, but what I claim as new is:—

5 1. In a toy vehicle including a body, a dragline therefor including a rod, a pull cord connected with the rod, and links pivotally connecting the ends of the rod with the body.

10 2. In a toy vehicle including a body, a dragline for the vehicle including a rod extending parallel with the body, links pivotally connecting the ends of the rod with the body, a pull cord, and an eye slidably connecting the pull cord with the rod.

15 3. The combination with a toy vehicle including a body, of means for pulling the vehicle forward or rearward in a straight path alongside of a child including a rod, links pivotally connecting the rod at spaced points to the body, a swivel 20 slidably mounted on the rod, and a pull cord connected to the swivel.

25 4. The combination with a toy vehicle including a body, of means for pulling the vehicle forward or rearward in a straight path alongside of a child including a bail having a straight rod and right-angularly extending arms terminating in eyes, eyes connected to the body, swivels connecting the eyes of the body with the eyes of the bail, a swivel slidably mounted on the bail, and a pull cord connected to the swivel.

30 5. A boat comprising a hull and a depending keel, the forward leading edge of the keel being provided with a bevel on one side extending from the upper end of the keel short of the bottom of the keel, and an oppositely directed bevel formed on the other side of the keel adjacent to its lower end.

35 6. The combination with a toy boat including a depending keel having its leading and trailing edges provided with a bevel on one side thereof extending from its top short of its bottom, and an oppositely directed bevel on its other side adjacent to the lower end thereof, of a dragline for the boat including a U-shaped bail, links pivotally connecting the ends of the bail to the keel, and a pull cord slidably mounted on the bail.

40 7. The combination with a toy vehicle including a body, of a dragline therefor including a rod, means pivotally connecting the ends of the rod with the body on the opposite sides of the vertical axis of the body and parallel with the horizontal axis of the body, and a pull cord slidably connected to the rod.

45 8. The combination with a vehicle including a body and front and rear pairs of wheels on the body, the front wheels being inclined in one direction and the rear wheels being inclined in an opposite direction, of a dragline for the vehicle including a rod, means pivotally connecting the ends of the rod with the body, and a pull cord slidably mounted on the rod.

50 9. A boat comprising a body and a depending keel, the keel having a flat plain face on one side and bevelled edges on the opposite side leading toward said flat plain face, and a dragline for the boat including a bail pivotally connected to the keel on the side having the bevel, and a pull cord slidably mounted on the bail.

JOHN BIRRELL.
